US0D1021911S

(12) **United States Design Patent** (10) **Patent No.:** **US D1,021,911 S**
(45) **Date of Patent:** **** Apr. 9, 2024**

(54) **DISPLAY STAND**

(71) Applicant: **Apple Inc.**, Cupertino, CA (US)

(72) Inventors: **Richard P. Howarth**, San Francisco, CA (US); **Wesley Bryan Hamm**, San Francisco, CA (US); **Federico F. Tio**, Santa Cruz, CA (US); **Frank Craig Thaler**, Santa Cruz, CA (US); **Russell John Kaaihue Heirakuji**, Cupertino, CA (US)

(73) Assignee: **Apple Inc.**, Cupertino, CA (US)

(**) Term: **15 Years**

(21) Appl. No.: **29/786,123**

(22) Filed: **May 28, 2021**

Related U.S. Application Data

(63) Continuation of application No. 29/470,931, filed on Oct. 25, 2013, now Pat. No. Des. 920,984, which is a continuation of application No. 29/434,593, filed on Oct. 15, 2012, now Pat. No. Des. 696,259.

(57) **CLAIM**

The ornamental design for a display stand, as shown and described.

DESCRIPTION

FIG. 1 is a top perspective view of a display stand showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines in the figures show portions of the display stand that form no part of the claimed design.

The dot-dash broken lines in the figures and the portions between pairs of dot-dash lines form no part of the claimed design.

1 Claim, 7 Drawing Sheets
